(57) **CLAIM**

The ornamental design for a handheld spectroscopy device head as shown and described.

DESCRIPTION

FIG. 1 is an isometric view of a new design for a handheld spectroscopy device head;

FIG. 2 is a front view of the handheld spectroscopy device head of FIG. 1;

FIG. 3 is a left side view of the handheld spectroscopy device head of FIG. 1;

FIG. 4 is a rear side view of the handheld spectroscopy device head of FIG. 1;

FIG. 5 is a right side view of the handheld spectroscopy device head of FIG. 1;

FIG. 6 is a top view of the handheld spectroscopy device head of FIG. 1;

FIG. 7 is a bottom view of the handheld spectroscopy device head of FIG. 1;

FIG. 8 is an isometric view of the handheld spectroscopy device head of FIG. 1, with side cover removed;

FIG. 9 is an isometric view of the handheld spectroscopy device head of FIG. 8, with side cover omitted from the drawing;

FIG. 10 is a front view thereof;

FIG. 11 is a left side view thereof;

FIG. 12 is a right side view thereof;

FIG. 13 is a rear view thereof;

FIG. 14 is a top view thereof; and,

FIG. 15 is a bottom view thereof.

(Continued)

The broken lines in the drawing views are included for the purpose of illustrating portions of the handheld spectroscopy device head that form no part of the claimed design.
